UNITED STATES PATENT OFFICE.

PERRY S. MARTIN, OF HARRISONBURG, VIRGINIA.

THERMOSTAT.

Application filed November 2, 1923. Serial No. 672,444.

This invention relates to thermostats and has for its object the provision of an all-metal thermostat which will be more compact and also more powerful for a given weight of metal than thermostats at present known.

A further object of the present invention is to provide a simple and efficient thermostat particularly adapted for use in an incubator. Still further objects of the present invention are pointed out in the specification and are particularly set forth in the claims following and relate generally to the specific forms of the elements and the shielding of the retaining elements by the elements of greater expansion.

Thermostats of the present day are generally of the elongated bar type and expansion of the metal in a single direction only is utilized. This might seem to be the correct practice since the amount of expansion of a piece of metal is determined solely by its length and consequently pieces of metal held in thermostatic relation by rivets say five inches apart would expand neither more or less than a similar bar of very different transverse shape if held by rivets spaced apart exactly the same distance.

For the ordinary run of work therefore but one dimension is useful but there are other conditions where it would seem advisable to take advantage if possible of the expansion of both the length and breadth of the metal and this is particularly true with thermostats intended for use in incubators and brooders where a considerable amount of power is required and in which the amount of space available for the thermostat is quite limited.

This taking advantage of the expansion of both the length and breadth of the metal is an area expansion and can be just as well considered along the lines of polar coordinates and described as radial and circumferential. That is; not only will the stresses accumulate radially at the center crossing and intersecting each other in all directions, but stresses will accumulate along the edges of the plates in a circumferential direction and these circumferential stresses will occur in zones all the way from the edges of the plates to their centers. All of these circumferential stresses will cut across all the radial stresses thus sort of bracing them and producing an arching or buckling that is well

nigh irresistible so long as the resistance to be overcome does not fracture the metal.

The thermostats at present in use in incubators are usually eighteen inches or more long and are consequently so large and clumsy that they have not been as widely used as the more compact fluid filled wafers which are not well suited for this use owing to their many disadvantages. By making my thermostat of all metal and by utilizing the expansion of both the length and breadth of the metal I have been able to devise a thermostat which is small enough to be interchangeable in the regulator brackets with the small round wafer type just mentioned.

In incubator and brooder use when the thermostat expands it must not only overcome the resistance of the elements but it must also move the damper or other mechanism to which it is attached in a rapid and positive manner and this frequently requires considerable power. In my device the amount of power is dependent solely upon the number of units used and I find in a number of tests made in large hatcheries that excellent results may be obtained with from two to four elements only four inches square; this because of the utilization of the crosswise and lengthwise expansion of the expanding members.

In the drawings:—

Figure 1 is a plan view of a thermostat embodying the present invention.

Fig. 2 is an edge view thereof.

Fig. 3 is a fragmentary section through the axis.

Fig. 4 is a view of a thermostat element having additional creases.

The sheets 10 and 11 are of steel or other strong and sturdy metal having a relatively low rate of expansion while the plates 15, 16, 17 and 18 are of a different metal and one having a relatively high rate of expansion. In its simplest form the sheets 15 to 18 inclusive are each perfectly flat and are secured in pairs on opposite sides of the supporting sheets 10 and 11; the adjacent members as 16 and 17 being secured together as by the rivet 20 which is located in the axis of the elements whereas the rivets 21 holding together the two expansive sheets and the supporting sheet between them are located at the corners of the squares.

An attachment means such as 23 is secured

at the center, that is, at the axis of one of the outer expansive members, such as 15 while at the other end of the pile the outer expansive element, for example 18, is provided in its center with a button 24 which presses against a movable portion of the mechanism to be operated by the thermostat. It will be obvious that as many units as may be desired may be connected together in which case the boss 24 will be replaced by a rivet 20 in the same manner and for the same function as the rivet between the members 16 and 17.

In their preferred form the expensive plates 15, 16, etc. are creased crosswise and diagonally as at 26 and 27 respectively so that the expansive sheets between rivets do not lie flat against the supporting plates as 10. The advantage of this construction is that the expansive force between adjacent rivets is carried to the center or axis of the thermostat in a more positive manner. I also find it advantageous to corrugate these sheets of expansive material radially from the center as at 28 as this, too, aids in insuring delivery of the entire expansion to the center of the sheet. The various sheets 10, 11, etc., may be mounted with their edges parallel but I prefer to stagger the various units as shown in the figures as this provides maximum accessibility of the expanding plates to the action of the heat.

While the drawings illustrate squares only, the idea can be carried out with any equilateral polygons such as triangles, pentagons, etc., or with round plates, or with any shape whatsoever that has substantial dimensions in all radial directions from the center. The sheets preferably should not have radial sections cut out along the edges as this would diminish the accumulation of circumferential stresses.

In incubators it is quite important that the thermostat shall act rapidly and this advantage I secure because of the protection given the supporting sheets 10 and 11 which are covered and practically enclosed by the sheets of high expansion and in this way a very high initial thrust is obtained as the relatively thin expanding sheets are affected very much quicker than the comparatively thick supporting sheets.

What I claim is:

1. An all-metal thermostat comprising three broad rectangular plates secured together at their corners the central plate having a lower coefficient of expansion than the outside plates, the diagonals of the rectangles crossing each other at the center substantially at a right angle.

2. A unit of a thermostatic pile comprising

ing a square sheet of low expansion metal and two sheets of higher co-efficient of expansion one located above and one below the first mentioned sheet, the three sheets being secured together only at their corners whereby longitudinal and transverse expansion of the outer sheets will cause the outer sheets to bow away from the supporting sheets through a central axis.

3. An all-metal thermostat comprising a plurality of units each unit comprising a supporting sheets of relatively low expansion and a plurality of sheets mounted on opposite sides thereof of higher expansion, the sheets of higher expansion being creased out from the supporting sheet, and radiating in more than two directions from the center.

4. An all-metal thermostat comprising a plurality of units each unit comprising a supporting sheet of relatively low expansion and a plurality of sheets mounted on opposite sides thereof of higher expansion, the sheets of higher expansion being creased out from the supporting sheet in a longitudinal and a transverse direction.

5. An all-metal thermostat comprising a plurality of units of substantial width each unit comprising a supporting sheet of relatively low expansion and a plurality of sheets mounted on opposite sides thereof of higher expansion, the sheets of higher expansion being diagonally creased out from the supporting sheet.

6. An all-metal thermostat comprising a plurality of equilateral polygon shaped units each unit comprising a supporting sheet of relatively low expansion and a plurality of sheets mounted on opposite sides thereof of higher expansion, the sheets of higher expansion being diagonally, transversely, and longitudinally creased out from the supporting sheet.

7. An all-metal thermostat comprising a plurality of units of substantial area in proportion to their greatest overall length each unit comprising a supporting sheet of relatively low expansion and a plurality of sheets mounted on opposite sides thereof of higher expansion, the sheets of higher expansion being corrugated radially out from the supporting sheet.

8. An all-metal thermostat comprising a plurality of units each unit comprising a supporting sheet of relatively low expansion and a plurality of sheets mounted on opposite sides thereof of higher expansion, the sheets of higher expansion being corrugated radially and in addition being creased in lines passing through the center of the pile at right angles to one another.
